(57) CLAIM

The ornamental design for a comb handle, as shown and described.

DESCRIPTION

FIG. 1 is a perspective view of a comb handle showing my new design;

FIG. 2 is a left side view thereof;

FIG. 3 is a right side view thereof;

FIG. 4 is a front view thereof;

FIG. 5 is a rear view thereof;

FIG. 6 is a top plan view thereof;

FIG. 7 is a bottom plan view thereof; and,

FIG. 8 is a perspective view with bristles attached.

The broken line showing in Figures is for illustrative purposes only and forms no part of the claimed design.
